UNITED STATES PATENT OFFICE.

JOSEPH W. HENNICH, JR., OF BOGALUSA, LOUISIANA.

CLEANSING AND PAINT-REMOVING COMPOUND.

1,201,181.

Specification of Letters Patent.

Patented Oct. 10, 1916.

No Drawing.

Application filed June 1, 1916. Serial No. 101,197.

To all whom it may concern:

Be it known that I, JOSEPH W. HENNICH, Jr., a citizen of the United States, residing at Bogalusa, in the parish of Washington and State of Louisiana, have invented certain new and useful Improvements in Cleansing and Paint-Removing Compounds; and I do hereby declare the following to be a full, clear, and exact description of the invention, such as will enable others skilled in the art to which it appertains to make and use the same.

The present invention relates to improvements in cleansing and paint removing compounds in which a number of cleansing ingredients are held in suspension in a suitable vehicle, such, for instance, as water, to be applied with a cloth, or otherwise, to painted, varnished, or other surfaces to restore the original luster.

The ingredients uniting to provide the improved compound are herein grouped into two formulas, the one being particularly adapted for application to remove varnish, grease, and accumulations of foreign matter; while the second formula, which includes the elements of the first formula, has been found to yield excellent results in removing paint and the like.

30 The first formula consists in a composition of matter containing benzol, acetone, caustic soda, and a vehicle, such as water. These ingredients are preferably united into the compound in the following proportions:—benzol, one pint; acetone, one pint; caustic soda, one pound; and water, in about three quarts, to complete a gallon of the mixture.

40 The second formula consists preferably of benzol, acetone, paraffin, nitric acid, acetic acid, caustic soda, and a vehicle, such as water. Such ingredients are advantageously mixed together in the following proportions:—caustic soda, one and one-half pounds; paraffin wax, one-quarter of a pound; benzol, one pint; acetone, one pint; acetic acid, two ounces; nitric acid, one-half of an ounce; and water, two and three-fourths quarts.

50 The compositions of matter, as com-

pounded in accordance with the above formulas, have been put into practical use; and having been thoroughly tested, have been found to produce excellent results; such compounds yielding distinct advantages over other compounds purporting to produce similar results, and of which latter compounds I am aware there are a variety in the trade.

The compounds as now known and in use are of a noxious and sickening odor, which is found to have an injurious effect on the persons using them, and in many cases such compounds contain ingredients poisonous to the skin. Moreover, compounds as now in use, are quite generally inflammable and explosive, and on this account dangerous, while evaporating and losing strength rapidly. Furthermore, after applying such compounds as are now in use containing turpentine, benzene, gasolene, or alcohol, the paint must be subsequently removed by the use of putty knives or scrapers; while the compound, as provided in accordance with the second formula of the present invention, so softens the grease, dirt, varnish, paint, or the like, as to permit the same to be readily removed with water applied by a brush, sponge, or hose.

The present compounds have been put to practical tests in removing grease and dirt from railroad cars, tanks, etc., and have been found to yield excellent results, accomplishing the work quickly, with less material, and with a saving of time and labor over results heretofore obtained. The compounds have no disagreeable or noxious odor, and their application is attended without any danger, they being non-explosive and non-inflammable.

It is to be understood that the invention is not confined to the precise proportions herein stated as obviously these proportions might be varied without departing from the spirit of the invention; and I reserve the right to make such changes in the ingredients and proportions as may come within the scope of the appended claim.

I claim:

A composition of matter for the herein

described purposes, the constituent ingredients of which in substantially the proportions mentioned are: caustic soda, one and a half pounds; paraffin wax, one quarter of 5 a pound; benzol, one pint; acetone, one pint; acetic acid, two ounces; nitric acid,

one half of an ounce; and water, two and three quarters quarts; substantially as described.

In testimony whereof, I affix my signature.

JOSEPH W. HENNICH, JR.
